ment Company, Minneapolis, Minn., a corpora-
tion of Delaware

Application April 13, 1940, Serial No. 329,516

9 Claims. (Cl. 22—10)

This invention relates to a device for supporting, manipulating and drawing sand cores such as used in foundry work.

The primary object of the invention is to provide a simple, compact and efficient machine or device by the use of which a core box may be supported in position for blowing or forming the core, turned over therefrom, and the core then drawn from the box, all in such convenient and easy manner that one man may carry out the operation no matter how large the core may be. A further object is to provide a machine of this kind which may be readily arranged as an attachment for a core blowing machine to greatly facilitate the operation thereof, but which may also be used as an entirely separate turn-over and draw machine in molding and core making. Still a further object is to provide a machine having numerous advantageous features of construction and operation as will appear in the course of the following specification.

These and other more detailed and specific objects will be disclosed in the course of the following specification, reference being had to the accompanying drawings, in which—

Fig. 1 is a frontal elevation of our core drawing device arranged as an attachment for a conventional core blowing machine and with the core box shown as in position for entrance into the machine.

Fig. 2 is a horizontal section along the line 2—2 in Fig. 1, and also showing the core drawing device in dotted lines as swung into the machine in position for blowing a core.

Fig. 3 is a front view of the assembly showing the core drawing device swung into the machine and with an upper portion of the latter broken away.

Fig. 4 is a detail perspective view of the tapered pin or wedge used for locking the drier plate on the core previous to its being turned over and drawn.

Fig. 5 is a fragmentary detail elevation showing a core drawn by the device.

Fig. 6 is a fragmentary detail side view, partially in section, showing a drier plate placed on the core ready for drawing.

Fig. 7 is an enlarged vertical cross section through one side of the core drawing device showing the anti-friction roller mounting therein.

Fig. 8 is a fragmentary elevation of the rear portion of the blower machine table showing the latch mechanism for retaining the core box in alignment therewith.

Referring now more particularly and by refer-

ence characters to the drawings, A designates generally a core blowing machine with which is used our core drawing device B. It is to be understood, however, that our device may be used as well as an entirely separate and distinct machine or in combination with other foundry equipment as may be desired or found expedient.

The core blowing machine A is of conventional form and includes a base 10 and a head 11 supported thereabove by upright posts 12. The table 13, upon which the core box is usually placed or clamped, is movable in a vertical direction by air pressure in order to lift the box into sealing engagement with the blower plate 14 on the overhead sand container 15. In this position sand is blown from container 15 by compressed air into the core box and the box is then lowered by causing the table 13 to descend. The box may then be removed for drawing the core and placing it upon a drier plate and transfer to the usual rack. The sand is contained usually in a hopper 16 beneath which the container 15 may be shifted for periodic refilling therefrom. The foregoing is the usual operation of such machines, but it will be apparent that the operation of removing the core box from the machine for drawing is one consuming considerable time and where the box and core are heavy it is a laborious undertaking at best.

Turning now to the construction of the turn-over and draw device B, the same in the form illustrated is seen to comprise two main units—the core box carrier member or frame 17 and the supporting or mounting frame 18. The latter, forming as it does the base upon which other parts are mounted, will be described first.

A rigid back or cross member 19 carries at its vertical, transversely spaced sides the guide and roller boxes or members 20 in which are mounted for vertical reciprocating movement the posts 21. The lower ends of these posts are rigidly connected to and carried upon the ends of a crosshead or yoke 22 having an intermediate upwardly arched portion 23 secured to the plunger 24 of a lifting jack 25. The cylinder 26 of this jack 25 is supported upon a lower foot portion 27 of the back member 19, and air under pressure may be admitted to the cylinder by air line 28 to raise the posts 21 upon the yoke 22. Relief of the air pressure will of course lower this assembly as will be understood.

Arranged within the members 20 are inner rollers 29 having concaved faces for engaging and supporting the posts 21 (see Fig. 7) and these rollers are mounted upon eccentric pins 30 in

such manner that, by turning the pins, the rollers may be shifted toward the posts to take up wear. Outer, straight rollers 31 are also provided in the members 20 and project at opposite sides therefrom through slots 32 defined by the removable cover plates 33. These rollers may likewise be mounted upon eccentric pins 34 and their function will hereinafter appear.

A pair of supporting beams or arms 35 are extended outwardly in spaced relation from the back member 19 and are braced by angular brace bars 36 to stand rigidly in the horizontal positions shown, these beams constituting the draw table, as will be described. A cross member 37 at outer ends of the beams 35 supports the valve 38 to which the air line 28 is connected, and by which operation of the jack 25 is controlled.

A bracket arm 39 is extended from one side of the foregoing assembly and at its free end is forked at 40 to embrace the upper section 41 of a mounting bracket 42 secured by clamps 43 to the head supporting posts 12 at one side of the core blowing machine. A vertically axised pivot pin 44 is removably mounted through suitable apertures in the forked end 40 of the arm 39 and both upper and lower sections or bars 41 and 45 of the bracket 42 to thus support the device B for swinging movement in a horizontal plane with respect to machine A. A caster wheel 46 mounted beneath the foot portion 27 of the back member 19 aids in supporting the device but permits ready swinging movement thereof.

The bracket 42 is of heavy rigid construction and at the forward end is bifurcated to provide the vertically spaced bars 41 and 45 aforesaid and thus to provide bearing support for both upper and lower portions of the fork 40.

The frame 17 is pivotally supported on the posts 21 and comprises elongated flat side bars 47 from medial portions of which are extended on one side the apertured ears or lugs 48 which are pivoted upon a cross rod 49 extended through the slightly flattened upper ends of the posts. On the opposite sides of the bars 47, also near the centers thereof, the brackets 50 are secured to support the core box mounting plate 51 at right angles to the length of the bars.

The core box shown in the drawings is of the horizontally split type and comprises a bottom portion 52 which is secured to the plate 51 and the top or cover 53 which is secured in inverted position to the sand container 15 of the core blowing machine. The type and shape of box used of course will vary widely in practice, and for convenience sake the bottom portion 52 will be hereinafter referred to simply as the core box.

An air line 54 of flexible nature is connected between the valve 38 and any suitable service connection of the machine A as represented at 55, and it is understood that the machine has all of the necessary air supply connections and controls usually provided although they are not herein shown.

In the operation of the assembly thus far described, the core blowing machine A is of course loaded with sand in the usual manner, and the container 15 filled from hopper 16. The construction and proportions of the frames 17 and 18 and location of the pivot 44 are such that the core drawing device constituted by the frames may swing outwardly away from the machine A, and in the position shown in Fig. 1 the box may be mounted on the plate 51 in position clear of the blowing machine. The entire device B is then swung inwardly on pivot pin 44 so that

the core box enters the machine A over the table 13 and to a position properly aligned with the sand container 15. The table 13 is now raised sealing the core box against its cover 53 or the blowing plate 14, and the sand is blown solidly into the box by manipulation of the blower valve on the machine in the usual manner. As the table 13 raises it of course contacts the mounting plate 51 and raises the entire frame 17 along with the posts 21 and when the core is completed lowering of the table allows these parts to descend clearing the box and core from the sand container and finally clearing the table below the plate 51.

The device B may then be swung as a unit outwardly clear of the machine carrying out the box and completed core ready for the next operation. This swinging movement of the core drawing device although carried out by hand in the set up shown, might readily be done by air power, by suitable connection of an operating unit (not shown) with the arm 39 or the like, and such modification of the structure is considered to be within the scope of the present invention.

The core as it now stands must be removed from the box and for this purpose we first place the usual drier plate 56 (shown in Fig. 6 and of course adapted in shape and size to the particular box in use) over the core and secure it tightly in place by inserting an elongated tapered pin or wedge 57 through a diametrical slot 58 in a central post 59 extended upwardly from the core box. The pin thus holds the drier plate 56 in place, and the entire frame 17 may now be turned over, or flopped over, until the box and core extend out over the draw table formed by the beams 35. As shown in Fig. 5 the drier plate 56 (now underneath) comes to rest at this time upon removable bars or fillers 60 placed on the beams 35 and, the pin 57 being removed, the valve 38 is now opened admitting air to the jack 25 causing the same to move the posts 21 upwardly. This action raises the frame 17, causing the core box to be drawn from the core represented at C in Fig. 5, and the core on the drier plate may then be removed and placed on the drying rack for transport to the ovens. Relief of the air pressure in the jack 25 will now return the frame 17 to lowered, operative position, and it may be turned over to again enter the core blowing machine to form the next core.

The entire operation of swinging the box into the machine, blowing the core, retracting the box, putting a drier plate in place, turning over the box, drawing and removing the core and returning the box to position for the next operation may be carried out smoothly and rapidly by the operator, and it will be apparent that even the heaviest and largest of cores may now be handled readily and quickly by one man.

The outer rollers 31 bear against the side bars 47 as the frame on the frame 17 is raised and lowered in either position and provide proper alignment of the frame as well as reduce wear on the side bars.

To facilitate the drawing operation, vibrators or knockers of any suitable form (not shown) may be arranged to engage the box and drier plate in well known manner. The draw table may also be equipped with equalizers of well known type for ensuring perfect alignment and proper drawing of the core. In lieu of the pin 57 the drier plate 56 may be clamped on the box by air clamps such as are ordinarily used in

core blowing and drawing machinery. The entire core drawing device may be readily removed from the machine by removing the pivot pin 44, and by use of a suitable support the device may be utilized as a separate turnover and draw machine.

As the core box enters the blowing machine and the table 13 starts to rise, there is a tendency for the box to swing upwardly slightly on the pivot 49. The box will of course be leveled when it strikes the upper section 53, but an uneven wear results, and to overcome this we provide (Fig. 8) a latch 65 arranged at the rear of the table 13 to engage a loop or hook 66 carried by the mounting member 51. As the box is swung into the machine now this hook 66 slips beneath the latch 65 to hold the box in perfect alignment with the table 13. The latch 65 is carried at the upper end of an arm 67 pivotally mounted at 68 on the rear side of the table and spring set by coil spring 69 to stand in the position shown. However, this spring permits the arm 67 to oscillate slightly as the hook 66 cams beneath the rounded end 70 of the latch.

The latch itself is pivoted at 71 on the upper end of the arm 67, but is normally held in rigid position by the safety shear pin 72. Should any unusual strain occur on the latch or the box fall thereon, this pin will shear off and the spring 73 will pull upon the latch to swing it into the clear upon the pivot 71.

It is understood that suitable modifications may be made in the structure as disclosed, provided such modifications come within the spirit and scope of the appended claims. Having now therefore fully illustrated and described our invention, what we claim to be new and desire to protect by Letters Patent is:

1. A device of the character described, comprising a base frame, upright guide members at the sides thereof, posts slidably supported in the guide members for up and down movements, side bars pivotally mounted on the posts for swinging movements with respect thereto about a horizontal axis, a core box mounted on the side bars and movable therewith from one side of the frame to the other through a range limited by engagement of the side bars with the base frame, means for raising the posts and side bars for drawing a core from the core box in the inverted position thereof at one side of the frame, and means for receiving and supporting the core as the box is drawn therefrom.

2. A device of the character described, comprising a base frame, upright guide members at the sides thereof, posts slidably supported in the guide members for up and down movements, side bars pivotally mounted on the posts for swinging movements with respect thereto about a horizontal axis, a core box mounting means secured to the side bars and extended at right angles therefrom, a core box secured to the said mounting means and movable with the side bars from a horizontal position at one side of the frame to an inverted horizontal position at the opposite side, means extended from the frame for supporting the box in the latter position, and means for raising the posts and side bars and drawing a core from the box upon the said supporting means.

3. A device of the character described, comprising a base frame, upright guide members at the sides thereof, posts slidably supported in the guide members for up and down movements, side bars pivotally mounted on the posts for swinging movements with respect thereto about

a horizontal axis, a core box mounted on and extending from the side bars for movement therewith from one side of the frame through a vertical plane to the other side to thereby

5 invert the box, a table extending from the base frame for supporting the core box in the inverted position, and a jack connected to the base frame and the posts for urging the posts upwardly and drawing the inverted core box from the table.

4. A device for manipulating a core box, to turn over and draw a core therefrom, comprising spaced upright guide members, posts slidably mounted in spaced relation in the guide

15 members for up and down movements, a core box carrier frame comprising side bars pivotally mounted on the posts for movement in the vertical plane from upright positions at one side of the guide members to inverted upright positions

20 at the opposite sides, a core box supported by the side bars for turnover movement therewith from a core receiving position to an inverted core drawing position, anti-friction rollers journaled in the guide members for engaging the posts and for engaging the side bars in their

25 upright position at either side of the guide members, and means for vertically adjusting the posts and side bars with respect to the guide members.

30 5. A device for supporting a core box in a core blowing position and for inverting the box to draw the core, comprising a supporting frame, a carrier frame, means for mounting the core box in the carrier frame, spaced upright mem-

35 bers mounted for up and down movements in the supporting frame and pivotally supporting the carrier frame for moving the core box from core blowing position to inverted core drawing position, means for rigidly supporting the core

40 in the core drawing position, means for raising the upright members and carrier frame to draw the core box from the core, and separate guide means in the supporting frame for engaging and guiding the upright members and carrier frame in their up and down movements and in both the core blowing and drawing positions of the parts.

6. The combination with a core blowing ma-

chine for forming a core in a core box and in-

50 cluding a table, of a core box supporting and manipulating device comprising a carrier mem-

ber pivotally supported at one side and having means for mounting the core box, means for swinging the carrier member into the machine to move the core box across the table toward the rear side thereof, the said carrier member hav-

55 ing a hook member on the side opposite to its pivotal supports and adapted to come to rest adjacent the rear of the table, and a latch mem-

ber carried by the table at the rear thereof for downwardly engaging the hook member and holding the core box in horizontal alignment with the table.

7. A device for supporting and manipulating a core box, comprising a frame having upright

65 guide members, posts mounted on said guide members for upward and downward movements with respect thereto, means for raising and lowering the posts, side bars pivotally connected at medial points to upper end portions of the posts

70 and movable upwardly and downwardly in connection therewith, means for supporting the core box on the side bars in a position substantially

at right angles thereto, the said side bars being movable from upright positions with one end in engagement with one side of the guide mem-

bers to a turned over position with their other ends in engagement with the opposite sides of the guide members to thereby invert and revert the core box carried by the side bars, and the said side bars having guiding engagement in either position with the respective sides of the guide members as the post and side bars move upward and downward.

8. A device for supporting and manipulating a core box, comprising a frame having upright guide members, posts mounted on said guide members for upward and downward movements with respect thereto, means for raising and lowering the posts, side bars pivotally connected at medial points to upper end portions of the posts and movable upwardly and downwardly in connection therewith, means for supporting the core box on the side bars in a position substantially at right angles thereto, the said side bars being movable from upright positions with one end alongside one face of the guide members to a turned over position with their other ends alongside opposite faces of the guide members to thereby invert and revert the core box, rollers journaled in said opposite faces of the guide members for engaging the ends of the said side

bars to limit swinging movements thereof and to guide the bars in their upward and downward movements, and the said rollers being adjustable in horizontal planes outwardly and inwardly with respect to said opposite faces of the guide members.

9. A core box manipulating device for a core blowing machine having a table, said device comprising a carrier frame pivotally supported at one side and having means supporting the core box in horizontally extending position, the said carrier frame being movable to swing the core box into the machine over the table thereof, a hook member on the core box mounting means, a latch adapted for downward engagement with the hook member to prevent upward movement of the core box relative to the table, means yieldably supporting the latch to permit its engagement with the hook member as the core box swings over the table, and a shear pin arranged to normally but releasably hold the latch in position for engaging the hook member.
